DIRECTIONAL ANTENNA SYSTEM

Gustav Renatus, Berlin, Germany, assignor to
Telefunken Gesellschaft für Drahtlose Tele-
graphie m. b. H., Berlin, Germany, a corpora-
tion of Germany

Application November 15, 1935, Serial No. 49,885
In Germany November 17, 1934

7 Claims. (Cl. 250—11)

The present invention relates to a directional antenna system for radiating singularly or uniformly polarized waves and having several single radiators connected to a parallel wire connection line, and in which a reflecting surface is placed in back of the radiation plane or radiation planes.

For the directed radiation of short waves, antenna systems are often used consisting of several single radiators connected to an energy line (umbrella antenna, or beam). An example of the embodiment of this antenna shape is shown in Fig. 1 in which five horizontal dipoles H_d are connected to a vertical connection line V_d . The antenna system may be fed from below in such manner that the energy furnished by a high-frequency transmitter is supplied across an energy line Z connected to the connection line V_d . The antenna arrangement may also be fed at the electrical center point thereof across an energy line Z' , for instance at the connection point of the central horizontal dipole H_d . If the same arrangement is to be used for directive reception, in place of the transmitter, a receiver is to be connected to the energy lines.

In analyzing the radiation field of such a directional antenna, it will be found that in the arrangement shown by way of example, the radiated waves are predominantly polarized in horizontal direction, while a not inconsiderable part with vertical polarization is also present. These vertically polarized waves originate in the vertical connection lines between the single radiators. Although these lines are relatively close to each other, the relative distance thereof can no longer be neglected in the case of short waves. There results therefrom a not inconsiderable radiation with a polarization corresponding to the geometrical arrangement of said lines.

In many cases, for instance, for increasing the selectivity or for bridging obstacles (arrangements of masts, forests) oscillations polarized in one direction only are desired. In a particular case it may also be desirable to send a message or a warning signal with differently polarized radiations in various directions. In such cases it is indispensable that the radiated waves be unequivocally or uniformly polarized.

The subject matter of the present invention offers a means for attaining this end. This directional antenna system, according to the invention, is characterized by the fact that the parallel wire connection line (connection lines) of the single radiators are arranged in back of the reflecting layer, and that the single radiators are

fed by means of lines extending at right angles to and through the reflecting layer.

Examples of embodiments of the inventive idea are represented in Figs. 2 to 9.

In the drawing, Fig. 1 illustrates a known type 5 of antenna; Fig. 2 illustrates a front view of a multiple dipole antenna system in accordance with the invention; Figs. 3, 4 and 7 illustrate side views of a system in accordance with the invention; Figs. 5, 6a and 6b illustrate top plan 10 views of an antenna system in accordance with the invention; Fig. 8 illustrates an airplane provided with an antenna system in accordance with the invention; and Fig. 9 illustrates a receiver 15 equipped to receive differently polarized components of waves radiated by an antenna system of the invention.

In order to obtain at the radiator the same electrical conditions as before, the dipoles H_d are connected to the connection lines V_d by means 20 of through lines S , preferably chosen $\lambda/2$ in length. However, through lines having the length $\lambda/4$ connected in the current loop of the connection lines are also suited. The through lines may be fixedly secured in or at the reflecting layer F with sufficient insulation therebetween, and at the same time they may serve as support for the dipoles and for the connection lines. Where it is intended to change the distance a_1 of the dipoles, or the distance a_2 of the 30 connection lines from the reflecting surface F , for instance at wave change, the through lines or the sections of the through lines may be adapted with varying length. This can be accomplished in a simple manner, by placing the radiators or 35 lines over the through lines S by means of tubular sleeves R having groove guides. Note Fig. 4. The through lines S may also be chosen of such length that at the place of fastening, there is an insulator bushing I which is located at a point of 40 low high-frequency potential relative to ground. If the radiation of the connection line is to be suppressed, the connection lines placed in back of the reflecting layer may be shielded, for instance in such manner that they are covered with 45 a tubing having the radius $\lambda/8$, as indicated in Fig. 5. The provision of shielding at a distance of $\lambda/8$ from the conductor system places the radiated and reflected field in phase opposition.

See treatise by F. Sammer "Wirkungsweise von 50 Drahtreflektoren", Telefunken Zeitschrift No. 1929, volume 53, page 66, bottom.

It is, however, also possible to utilize the vertically polarized radiation of the connection line in that it is caused to radiate eventually in con- 55

nection with a parabolic cylindrical reflector P in whose focal line the connection line is placed. Such an arrangement is shown in the Figs. 6a and 6b and 7. This arrangement may, for instance, 5 be used in airplanes as approaching and warning transmitter (Fig. 8) in such manner that a definite signal with horizontal polarization is given in the direction of travel and that the same signal eventually slightly weaker and having 10 vertical polarization is given in the direction to the point of departure.

On another airplane or on the flying field, a directional antenna system, according to the invention, may be used as a receiving arrangement. 15 In this case the energy line of the receiver will suitably be connected in the center point of the parallel wire connection line, in order to enable the antenna arrangement to be swung or turned about its electrical center point. In the operating position, the receiver arrangement will be disposed at an angle of about 45°, in order to enable the reception of components of the two directions of polarization of the transmitter, and which are at right angle to each other. Note 20 Fig. 9. In turning the receiver arrangement it can be ascertained whether the respective aircraft flies away or towards the observation point. Such short wave directional antennas are ordinarily set up at exposed places so that danger 25 exists that, due to wind and weather and also due to other exterior influences, the tuning and the radiation property may slightly change. It is therefore advisable to surround the entire antenna arrangement with an electrically suitable insulation material or to embed the same 30 therein.

The idea of the present invention is not limited to the examples of construction above presented.

40 What is claimed is:

1. An antenna comprising a dipole antenna arranged in a substantially vertical plane, a reflecting surface for said dipole, and a two-conductor line connected to said dipole and extending through said surface, the conductors of said line being arranged in a plane substantially perpendicular to the plane of said dipole, a two-conductor energy feeder for said line arranged on the opposite side of the reflecting surface as 45 said dipole antenna, and a curved reflector on the opposite side of said surface for directing the radiations from said feeder.
2. An antenna comprising a dipole antenna arranged in a plane, a reflecting surface for said 50 dipole, and a two-conductor line connected to said dipole and extending through said surface, the conductors of said line being arranged in a plane perpendicular to the plane of said dipole, a pair of parallel conductors for feeding said line 55 on the opposite side of the reflecting surface as said antenna, said pair of conductors being perpendicular to said line and to said antenna, and 60

a shield tube having a radius approximately equal to one-eighth of the length of the communication wave encircling in part said pair of conductors.

3. An antenna comprising a plurality of parallel dipole antennas located substantially in the same plane, a reflecting surface for said antennas, a pair of connections for each dipole extending from the dipole through said surface and arranged at right angles to the dipole, said connections having a length substantially equal to half the length of the communication wave, and a feeder system located on the side of said surface opposite the antennas and coupled to said connections. 15

4. An antenna comprising a dipole arranged in a plane, a reflecting surface for said dipole, and a two-conductor line connected to said dipole and extending through said surface, the conductors of said line being perpendicular to said dipole, a feeder line located on the side of said surface opposite said dipole and connected to said two-conductor line, said feeder line being perpendicular to said two-conductor line, and a parabolic reflector for said feeder line, said parabolic reflector being arranged to direct the radiations from said feeder line in a direction opposite to the energy radiated from said dipole. 20 25

5. An antenna comprising an antenna having two arms arranged in a horizontal plane, a substantially vertical plane reflecting surface for said antenna, a two-conductor line connected to said antenna and extending through said surface, a vertical feeder line located on the side of said plane surface opposite said antenna and connected to said two-conductor line, and high frequency apparatus coupled to said feeder line. 30 35

6. An antenna comprising a dipole antenna arranged in a plane, a reflecting surface for said dipole, and a two-conductor line connected to said dipole and extending through said surface, the conductors of said line being arranged perpendicular to said dipole, a two-conductor energy feeder for said line arranged on the opposite side of the reflecting surface as said dipole antenna, 40 and a curved reflector on said opposite side of said surface for directing the radiations from said feeder, said feeder being located in the focal line of said curved reflector.

7. An antenna comprising a dipole antenna arranged in a plane, a reflecting surface for said dipole, and a two-conductor line connected to said dipole and extending through said surface, the conductors of said line being arranged in a plane perpendicular to the plane of said dipole, 50 a two-conductor energy feeder for said line arranged on the opposite side of the reflecting surface as said dipole, and a curved reflector located on the opposite side of said surface for each conductor of said energy feeder for directing the 55 radiations from said feeder. 60
